UNITED STATES PATENT OFFICE.

GEORGE L. LAMB, OF NAPPANEE, INDIANA.

TROUBLE LIGHT FOR AUTOMOBILES.

Application filed September 28, 1921. Serial No. 503,715.

To all whom it may concern:

Be it known that I, GEORGE L. LAMB, a citizen of the United States, residing at Nappanee, in the county of Elkhart and State of Indiana, have invented certain new and useful Improvements in Trouble Lights for Automobiles; and I do hereby declare the following to be a full, clear, and exact description of the invention, such as will enable others skilled in the art to which it appertains to make and use the same.

The present invention relates to trouble lights particularly adapted for use upon automobiles.

An object of the present invention is to provide a trouble light which is portable and which may be attached to the belt or other clothing of the person for holding the light in a desired position to reflect rays of the light onto the part of the mechanism or automobile desired when making adjustments, repairs or the like at night.

Another object of the invention is to provide the light with a support or standard which may be folded out of the way when not in use, and which is adjustable for supporting the light upon a flat surface at a desired height.

Another object of the invention is to provide a combined cap and reflector so arranged as to protect the bulb and adjacent parts of the lamp when not in use and arranged to form a reflector for directing the rays of the light and concentrating the rays upon part of the mechanism which it is desired to work upon.

The invention still further aims at the provision of a trouble light embodying the above characteristics and which has an extensible cable or electric conductor which may be attached at one end to a socket fixed upon the instrument board or other suitable location on the vehicle, and which at its other end is connected to the trouble light. The cable is arranged upon the trouble light in such manner that the portion of the cable when retracted is entirely housed and pro-

tected within the casing of the trouble light and is held therein to expose desired lengths of the cable for facilitating the handling of the lamp without danger of injury to the cable and lamp.

With the foregoing and other objects in view, the invention will be more fully described hereinafter, and will be more particularly pointed out in the claims appended hereto.

In the drawings, wherein like symbols refer to like or corresponding parts throughout the several views.

Fig. 1 is a perspective view of a trouble light constructed according to the present invention, the same being adjusted in position for use when supported upon a flat surface;

Fig. 2 is a rear elevation of the same with the cap closed;

Fig. 3 is a vertical longitudinal section taken through the lamp in the open and set up position of Fig. 1;

Fig. 4 is a transverse section taken on the line 4—4 of Fig. 3 through the upper portion of the lamp;

Fig. 5 is a similar view taken through an intermediate portion of the lamp on the line 5—5 of Fig. 3;

Fig. 6 is a fragmentary sectional view taken through the lower end of the casing, showing a portion of the spring and its cap mounted therein;

Fig. 7 is a detail perspective view of the combined hook support and guideway for the adjustable stand; and,

Fig. 8 is a fragmentary sectional view through a portion of the guideway and stand as applied to the side of the casing.

Referring to the drawings, 10 designates a casing or drum of preferably cylindrical construction and which is open at its lower end and provided at its upper end with an annular top wall 11 having at its inner marginal edge an upstanding annular flange 12. Arranged centrally within the casing 10 is a drum 13 which may be of uniform diameter throughout and which is adapted

to be introduced into the lower open end of the casing and fitted at its upper end into the flange 12 for holding the drum rotatably therein.

5 The drum 13 has an upper flange 14 which is spaced from the upper extremity of the drum and which has an annular ring 15 at its inner marginal edge by means of which the flange 14 is secured to the drum. The 10 ring 15 extends upwardly from the flange and forms an abutment or bearing surface for contact with the lower side of the top wall 11 of the casing to limit the upward insertion of the drum in the casing. The 15 lower end of the drum 13 is provided with a flange or disk 16 which not only closes the lower end of the drum, but which extends radially therebeyond and forms an opposite confining wall cooperating with 20 the flange 14 for accommodating an electric cord, a cable or the like which may be wound upon the drum.

The disk 16 is provided at its central portion with a depending hub 17 which has 25 bearing through the central portion of a cap 18 which is fitted to the lower end of the casing 10, and which, as shown, may extend at its marginal portion into the drum and be secured detachably therein by one 30 or more set screws 19. The cap 18 is of sufficient depth to contain and house a spiral spring 20, and the latter at its outer end is anchored to the cap 18 by overturning the outer end of the spring to form a hook 35 21, as shown in Fig. 6, and the hook is engaged over a tongue 22 which is secured to the inner peripheral surface of the cap 18 and engages the hook 21. The inner end of the spring 20 is also provided with a hook 40 23 adapted to engage in a longitudinal slot 24 formed in the hub 17 of the drum, the spring 20 thus normally urging the drum 13 to turn in one direction.

The upper open end of the drum 13 is 45 closed by an insulating block 25 of suitable electric non-conducting material, and the block is fitted snugly in the drum and spaced from the upper extremity thereof. The block is centrally apertured to form a socket 50 for receiving the plug 26 of an electric lamp 27, and the block 25 carries contacts 28 and 29 which are adapted to be engaged by the usual projections on the plug 26 when the latter is seated in the socket. A 55 reflector 30 of concave convex form is seated on the upper side of the block 25 and is apertured to receive the plug 26 therethrough, the source of light or bulb 27 being arranged above the reflector 30 as shown 60 in Fig. 3. The marginal portion of the reflector 30 fits into the top of the drum 13 and is frictionally held therein.

The casing 10 carries upon its upper end a cap 31 which is dome shape and which is

provided with a marginal flange 32 outstanding from the lower edge of the cap and adapted to seat upon the top wall 11 of the casing when the cap is closed. At the rear side of the cap 31, the flange 32 is stamped to provide a pair of upstanding 70 ears 33 against which engage a second pair of ears 34 which are stamped and turned upwardly from the top wall 11.

The cooperating pairs of ears 33 and 34 receive therethrough a pin 35 and a spring 36 mounted on the pin with one end engaging the rim of the cap 31, as at 37, and the other end 38 resting upon the wall 11. The spring 36 is thus placed under tension and normally urges the cap 31 into raised or 80 open position as shown in Figs. 1 and 3. The cap is adapted to be swung down into closed position against tension of the spring 36, and to hold the cap closed, a spring 85 latch 39 is mounted upon the forward side of the casing 10 with its nose projecting above the wall 11 sufficiently to receive the flange 32 therebeneath. A wear plate 40 is mounted upon the forward side of the cap 31 to engage beneath the latch 39 for taking 90 up frictional contact and wear which would otherwise be imposed upon the flange 32.

Wound upon the drum 13 is an electric cord or cable 41 with its inner end carried through the side wall of the drum 13 and connected to the spring contacts 28 and 29. The outer end of the cord 41 is threaded through a longitudinal slot 42 formed in the outer wall of the casing 10 and such free end of the cord may be carried to any suitable source of electric energy for either permanent or detachable connection thereto. The flange 14 of the drum is provided at suitable intervals in its periphery with notches or recesses 43 adapted to receive the 105 nose 44 of a spring pawl or latch 45 mounted upon the exterior side of the casing 10 and projecting through the casing at a point in registry with the flange 14. The spring latch or pawl 45 is preferably stamped from a single blank or strip of metal which is slotted lengthwise at one end to form by one branch the nose 44 and at its other branch an attaching tongue 46 which may be welded or otherwise suitably secured to the side 110 of the casing 10. The other end of the strip or blank provides a handle or thumb piece adapted to be depressed for swinging the nose 44 outwardly from the drum upon the flexing of the overturned attaching portion 46.

It will be also noted that the spring latch 39 may be welded to the exterior side of the drum and extends upwardly beneath the spring latch or pawl 45 to dispose these 115 members at the forward side of the casing and adjacent to the slot 42 for easy access.

Secured longitudinally to the back of the

casing 10 is a channel strip 47. As shown in Fig. 7, particularly, this channel strip 47 has at its upper end a shouldered locking tongue 48 of a width adapted to fit between 5 the pairs of ears 33 and 34 at the top of the casing and arranged to project beneath the top wall for anchoring the upper end of the channel strip to the casing. The strip 37 also carries an upstanding stop 49 against 10 which the cap 31 is adapted to engage when swung open, and the spring 36 is adapted to hold the cap against this stop.

At one edge, the strip 47 is rolled over to form a bearing 50 for receiving one end of a 15 hook 51 constructed of wire or the like and which projects downwardly to a considerable extent for engaging in a belt or in the clothing for supporting the casing on the body so that both hands may be free for 20 making adjustments and repairs.

The lower end of the channel strip 47 is provided with an opening 52 for the reception of a threaded stud 53 which is secured to the casing 10 and which projects rearwardly therefrom. The stud 53 carries a 25 thumb nut 54 adapted to be turned up against the outer side of the channel strip 47 for binding the latter against the rear side of the casing.

30 Slidably fitting in the channel strip 47 is a slotted arm or standard 55 having a side portion disposed at each side of the stud 53 and the latter forming an interlock between the arm 55 and channel strip 47. The 35 arm 55 is of such thickness that when the thumb screw 54 is turned up against the channel strip 47, the latter is caused to frictionally bind against the arm 55 and hold it in any desired position of adjustment. The 40 outer or lower end of the arm 55 is spread into a base or loop 56 of sufficient size or diameter to support the casing 10. Preferably, the standard 55 and the base 56 are formed from a single length of wire which 45 provides the base loop and the upstanding arm or standard with its side portions and intermediate slot. Preferably, a sheet metal clip 57 is adapted to the lower end of the standard 55 for holding the lower ends of 50 the standard from spreading and such clip may be provided with an apertured lug 58 bent at a suitable angle for engagement over a support, such as a screw, a nail or other suitable device found convenient for suspension of the lamp.

In use, the outer end of the cable 41 is connected to a source of electric energy and if it is desired to support the lamp upon the belt, the hook 51 is swung out into position 55 for engaging over the belt or other garment for suspending the lamp at the front of the person.

The spring latch 45 is depressed to release the drum 13 and the cord 41 is drawn

out of the casing to the desired length so that 65 the user may move about freely without danger of damage to the lamp. As soon as the desired length of the cable is drawn out, the spring latch 45 may be released so as to interlock with the notches 43 and hold 70 the drum from retrograde movement. During this time, the stand may be folded or retracted by loosening the thumb screw 54 and forcing the standard 55 up into the channel strip 47. The thumb screw 54 being then 75 tightened holds the standard 55 in this collapsed position.

The latch 39 is now sprung into releasing position and the spring 36 raises the cap 31 and supports it against the stop 49. The 80 cap 31 is of dome shape for the purpose of concentrating and reflecting the rays of light from the lamp 27 onto the object or location at which the light is desired.

If it is desired to use the lamp on the 85 ground, or on some other flat support, the standard is used and for this purpose the base 56 is rested upon the support and the casing raised upon the standard 55 to the desired height and clamped thereon when 90 such adjustment is obtained.

It is obvious that various changes and modifications may be made in the details of construction and design of the above 95 specifically described embodiment of this invention without departing from the spirit thereof, such changes and modifications being restricted only by the scope of the following claims:

What is claimed is:

1. In a trouble lamp for automobiles, a 100 casing, a drum in the casing, a cord mounted on the drum and projecting at one end through the casing, means for normally urging the drum to turn in one direction 105 for winding the cord thereon, means for locking the drum when the cord is extended, an electric lamp mounted in exposed position on the casing and connected to the cord, a spring pressed cap mounted upon the casing 110 adapted to be normally raised into position for reflecting rays of the lamp outwardly from the casing, and releasable means for holding the cap closed over the lamp when out of use for protecting the 115 lamp, substantially as described.

2. In a trouble lamp for automobiles, a 120 casing, a spring upright drum in the casing, a cord carried by the drum and projecting at one end through the casing for attachment to a source of electric energy, a lamp in the casing connected to the other end of the cord, said cord being adapted to be extended from the casing to the desired length, means for locking the drum upon 125 adjustment of the cord, means for supporting the casing on the clothing of the operator, and a combined closure and reflector

1
mounted on the casing for housing the lamp in one position of adjustment and for reflecting rays of the lamp outwardly from the upright in another position of adjustment, 5 substantially as described.

3. In a trouble lamp for automobiles, a casing, a lamp carried by the casing, a spring pressed cap mounted upon the casing arranged to protect the lamp and normally urged into open position for reflecting rays of the lamp outwardly from the casing, an attaching member mounted upon

the rear side of the casing, a standard adjustably mounted on the attaching member adapted to support the casing at various heights, and a hook pivoted to said attaching member for engagement in the clothing to suspend the casing on the person and adapted to be swung upon said attaching member into position against the side of the casing out of the way when not in use, substantially as described. 15 20

GEORGE L. LAMB.
